[57] CLAIM

The ornamental design for a container for liquids, as shown and described.

DESCRIPTION

FIG. 1 is a perspective view of a container for liquids showing my new design.

FIG. 2 is a front elevational view thereof.

FIG. 3 is a side elevational view taken from the right of FIG. 2.

FIG. 4 is a bottom plan view thereof.

The side opposite that shown in FIG. 3 is a mirror image thereof.

FIG. 1

FIG. 2

FIG. 3

FIG. 4
